United States Patent Office

Des. 198,520
Patented June 23, 1964

198,520

CATCH BASIN SCREEN

Joseph Kohorst, Rte. 1, Arcadia, Iowa

Filed Apr. 1, 1963, Ser. No. 74,245

Term of patent 14 years

(Cl. D91—3)

FIG. 1

FIG. 4

FIG. 5

FIG. 3

FIG. 1 is an elevational view showing my new design for a catch basin screen, the portions shown in broken lines being for illustrative purposes only,

FIG. 2 is an enlarged top view,

FIG. 3 is an enlarged side elevational view,

FIG. 4 is an enlarged bottom view, and

FIG. 5 is an enlarged end elevational view.

I claim:

The ornamental design for a catch basin screen, as shown and described.
